Harvey B. Eggleston

Inventor

C. Snow & Co.

UNITED STATES PATENT OFFICE.

HARVEY B. EGGLESTON, OF BROCK, MISSOURI.

CHURN.

SPECIFICATION forming part of Letters Patent No. 471,109, dated March 22, 1923.

Application filed June 30, 1891. Serial No. 398,071. (No. 1-1-1.)

To all whom it may concern:

Be it known that I, HARVEY B. EGGLESTON, a citizen of the United States, residing at Brock, in the county of Scotland and State of Missouri, have invented a new and useful Churn-Motor, of which the following is a specification.

The invention relates to improvements in churns.

- 10 The object of the present invention is to simplify and improve the construction of reciprocating double-dasher churning and to render the movements of the dashers positive and regular.
  - 15 The invention consists in the construction and novel combination and arrangement of parts, hereinafter fully described, illustrated in the accompanying drawings, and pointed out in the claims hereto appended.
  - 20 In the drawings, Figure 1 is a vertical longitudinal sectional view of a churn embodying the invention. Fig. 2 is a horizontal sectional view.
  - 25 Referring to the accompanying drawings, 1 designates a churn-body mounted on legs 2 and provided with a detachable cover 3, which has rising centrally from it a fulcrum-post 4, and is provided on opposite sides of the post 4 with openings 5 to receive dasher-rods 6.
  - 30 The dasher-rods are provided at their lower ends with suitable dashers 7, which are horizontally disposed and are provided with longitudinal blades 8, and the upper ends of the dasher-rods are reduced and are pivoted in
  - 35 openings 9 of a walking beam or lever 10. The lever 10 is recessed on opposite sides at 11 and is pivoted in a bifurcation 12 of the upper end of the fulcrum-post 4, and when the lever 10 oscillates the dasher-rods 6 are
  - 40 given a vertical reciprocation. One end 13 of the lever is extended beyond the body of the churn and is provided with an opening 14

in which is pivoted a reduced upper end 15 of a pitman 16, which has its lower end provided with a perforation to receive a crank-loop 17 of a shaft 18. The shaft 18 is journaled in the sides of the body and is arranged below the bottom thereof and has one end extended beyond the body and provided with the said crank-loop 17 and the crank-handle 50 19. When the shaft is rotated by the handle, an oscillating motion is imparted to the lever 10 and the dasher-rods are given a positive and regular motion, which is essential to an efficient churn.

It will be seen that a simple and comparatively inexpensive construction is provided and that a positive and regular movement is imparted to the dashers.

What I claim is—

In a churn, the combination of the body provided with a fulcrum-post rising centrally from its top and having openings on opposite sides of the fulcrum-post, the dasher-rod arranged in said openings and provided at their lower ends with dashers, the lever 10, fulcrumed intermediate its ends on the post and being pivotally connected to the upper ends of the dasher-rod and having one end extended beyond the churn-body, the shaft journaled in the body and being extended beyond the same and provided with a crank-loop and a crank-handle, and a pitman having one end connected to the crank-loop and its other end pivoted to the extended end of the lever, substantially as described. 75

In testimony that I claim the foregoing as my own I have hereto affixed my signature in presence of two witnesses.

HARVEY B. EGGLESTON.
